UNITED STATES PATENT OFFICE.

EDGAR B. STOCKING, OF WASHINGTON, DISTRICT OF COLUMBIA.

MECHANICAL STARTER FOR AUTOMOBILES.

1,168,916.

Specification of Letters Patent. Patented Jan. 18, 1916.

Application filed March 10, 1915. Serial No. 13,518.

To all whom it may concern:

Be it known that I, EDGAR B. STOCKING, a citizen of the United States, residing at Washington, in the District of Columbia, 5 have invented certain new and useful Improvements in Mechanical Starters for Automobiles, of which the following is a specification, reference being had therein to the accompanying drawing.

10 This invention relates to certain new and useful improvements in mechanical starters for automobiles and is an improvement upon my former application, Serial Number 768,894, filed May 20, 1913; the object being 15 to simplify the construction and to provide a starter with positive means for holding the revolute starting member in engagement with the pinion of the engine shaft.

Another object of the invention, is to 20 improve the starter operating means whereby the revolute starting member is moved in a path to intersect the path of travel of the engine shaft and out of said path by an endless cable to one lead of which is connected a lever for operating the same.

Another object of the invention is to provide novel means for throwing the revolute starting member out of engagement with the pinion of the engine shaft upon the back 30 firing of the engine causing a back kick so as to prevent accidental injury to the operator or the parts of the starter.

Another object of the invention is to provide a mechanical starter which can be 35 readily attached to any of the well-known makes of automobile, now in use.

Other and further objects and advantages 40 of the invention will be hereinafter set forth and the novel features thereof defined by the appended claims.

In the drawings—Figure 1, is a side elevation of an automobile partly in section, showing the application of my improved starter; Fig. 2, is a perspective of the operating cable showing its connection with the lever and the revolute starting member; Fig. 3, is an elevation of the starter and supporting plate showing the starter in its locked inoperative position ready to be operated; Fig. 4, is a similar view showing the revolute starting member thrown into mesh with the pinion of the engine shaft; Fig. 5, is a side elevation of the starter showing the pinion and coupling member of the engine shaft in section and the ordinary starting crank in position to start the en-

gine as well as the mechanical starter in order to enable the engine to be started independently by either the ordinary crank starter or the mechanical starter; Fig. 6, is 60 a section through the revolute starting member showing the manner of connecting the operating cable; Fig. 7, is a detail section through the lever showing the manner of connecting the ends of the cable thereto; 65 Fig. 8, is a side elevation of the hanger and revolute starting member partly broken away showing the parts in the position on the initial return movement; Fig. 9, is a perspective of the dog for throwing the 70 revolute starting member out of contact with the pinion of the engine shaft in case a kick back occurs, said member also operating the locking member for holding the revolute member in its contact with the pinion of the engine shaft; Fig. 10, is a perspective of the lock detached, for holding the revolute member in mesh with the pinion of the engine shaft; and Fig. 11, is a side elevation of the revolute member and 75 the dog showing the same in various positions in its movement into and out of mesh with the pinion of the engine shaft.

Like numerals of reference refer to like parts in the several figures of the drawings. 80

In the drawings, 1 indicates a plate or bar adapted to span the engine shaft 2 provided with brackets 3 at its ends for securing the same to the side bars 4 of the automobile frame which is the preferred form 90 of mounting the supporting plate, but it is, of course, understood that various other ways can be employed for securing the plate in position in respect to the pinion of the engine shaft, and I do not wish to limit myself to any particular manner of mounting the supporting plate. 95

The plate 1 is formed with an upwardly projecting portion 5 to one side of the fan shaft as clearly shown in Figs. 3 and 4, on which is pivotally mounted a hanger 6 upon a bearing stud 7 preferably secured in position thereon by a cotter pin 7' as shown. 100

The hanger is preferably formed of a pair of spaced side members 8 having apertured bosses adjacent their lower ends through which extends a bearing pin 9 on which is mounted a gear 10 between the side bars 8 of the hanger which is preferably mutilated. However, a complete gear can be used and I do not wish to limit myself 105 to the use of any particular form of gear as 110

in some instances, a mutilated gear has advantages over a complete gear.

5 The gear 10 is provided with an annular centrally disposed groove 11 formed by constructing the gear of a central hub portion having plates secured thereto, the marginal edges of which are cut to form teeth as clearly shown in Fig. 6.

10 A slot 12 is formed in the supporting plate 1 through which the bearing pin 9 for the gear 10 may be adapted to pass in order to guide and limit the hanger in its movements.

15 Seated within the groove 11 of the gear 10 is a cable 13 which is secured to the gear by forming a notch in the hub portion thereof into which the cable is pressed and over which passes a transversely disposed screw 14 as shown in Fig. 6. One end portion of 20 the cable passes upwardly over a guide pulley 15 arranged upon the bearing pin 7 of the hanger and then over the fan shaft around a guide pulley 16 which may be carried by an extension of the plate 1. The 25 other end portion of the cable 13 passes around a guide pulley 17 which may be carried by the hanger and the loop portion of the cable is carried by a pulley 18, adjustably connected to the dash or other suitable part of the automobile, as shown in Figs. 30 1 and 2, whereby the slack can be taken up.

35 The cable 13 is substantially an endless cable as the ends thereof are connected by a cable clamp 19 to a lever 20 pivotally mounted on a bracket 21 carried in this instance, by the motor base as shown in Figs. 1 and 2.

40 The lever 20 extends upwardly into the hood of the automobile and has connected to its upper end a pull cable 22 which extends through a suitably arranged opening formed in the dash of the automobile and which is provided with a stop 23 for limiting the movement of the pull cable so as to 45 control the throw of the lever 20; said cable having a handle 24 at its end which is adapted to be grasped by the operator so as to oscillate the cable in starting the machine, as will be later described.

50 The lever is normally held in the position shown in Figs. 1 and 2 by a coil spring 25 which is connected to the frame of the automobile at one end and to the lever at its opposite end.

55 From the construction so far described, it will be seen that I have provided a pivotally mounted hanger carrying a revoluble starting member which is connected to a cable operated through the medium of a lever and 60 a pull cable in such a manner that the revoluble starting member will be thrown into mesh with the pinion of the engine shaft when drawing upon the pull cable so that upon the continuous pull of the 65 cable, the revoluble member will be ro-

tated which in turn, will turn the engine over to start the same. After the handle 24 has been released by the operator, the spring 25 will return the lever 20 to its initial position and through the medium of the cable 70 the hanger and revoluble starter member will be returned to the initial or inoperative position.

75 In order to provide means for locking the hanger and revoluble starting member in inoperative position, I provide the outer bar of the hanger with a stud pin 26 upon which is yieldably mounted a hook 27 adapted to 80 coact with a pin 28 fixed on the projection 5 of the supporting plate 1 in such a position that on the return movement of the hanger and operating gear, the pin will be engaged by said hook so as to lock the hanger to provide positive means for locking the starting member in inoperative position. The hook 2 85 member in inoperative position. The hook 27 is provided with a finger 29 adapted to co-operate with a laterally projecting pin 30 carried by the gear 10 in such a manner that on the initial movement of the starting gear, the finger will be depressed so as to draw the hook 27 out of engagement with the pin 28 to release the hanger in order to allow the cable to swing the same with the gear into the path of travel of the pinion of the engine 90 shaft. The hook 27 is normally held in raised position by a coil spring 30', one end of which is connected to the hook and the opposite end to the cotter pin which extends through the bearing pin 7'. The pin 30 carried by the gear 10 also limits the movement of the gear by coming into contact with the opposite sides of the outer bar of the hanger 95 so that on the return movement of the hanger and gear, the pin rides under the finger 29 throwing the hook out of engagement with the pin 28 so as to allow the hanger to swing. The pin 30 rides on the finger 29 on the initial movement of the gear in such a manner that the hanger is 100 released from locked position, but the gear is prevented from being rotated until the pin carried thereby rides off of the end of the finger 29 and by continuing the pull on the cable, the hanger carrying the gear will be 105 thrown into mesh with the pinion of the engine shaft and rotated so as to turn the engine over.

110 In fitting the engine shaft to co-operate with the movable and revoluble starting member, I provide a clutch cup 31 with a pinion 32 carried by a slotted sleeve 33 extending into the clutch cup and securely fastened therein by the clutch pin 34 which is 115 held in position by cotter pins 35 or by screws passing through the clutch and into the sleeve. By this manner of fitting the engine shaft to co-operate with the starting member, the construction of clutch member 120 now in use upon automobiles is not changed 130

and the pinion is attached thereto in such a manner that the clutch head 36 of the starting crank 37 has free movement within the same, whereby a mechanical starter is provided which does not interfere with the operation of the crank starter now in use upon automobiles so as to enable the engine to be started either by the mechanical starter or the crank starter.

10 Pivots mounted upon the supporting plate 1 in the path of travel of the gear 10, is a dog 38 which may have a hooked end portion 39 adapted to coact with the sides of adjacent teeth of the gear 10, said hook portion being of such a shape that it straddles the opposed teeth of the gear when in horizontal position. The dog is held in its horizontal position by a flat spring 40 which bears upon the upper side of the same as 15 clearly shown in Figs. 3 and 4, and is capable of assuming any of the positions as shown in Fig. 11. This dog is for the purpose of throwing the revolute starting member out of mesh with the pinion of the 20 engine shaft at the completion of a starting operation or in case a back kick occurs. It will be seen that when the starting member is in its locked position, as shown in Fig. 3, the dog is normally in a substantially horizontal position and as the revolute starting member carried by the hanger is moved into mesh with the pinion of the engine shaft, the dog is engaged by the gear there- 25 of and on the continuous rotation of the starting member, the dog is carried upwardly into the position as shown at A as shown by dotted lines in Fig. 11, where it continues to ride over the teeth of the gear. At the completion of a starting operation 30 or in case a back kick should occur at any time in the starting operation, the meshing starting member is reversed so as to throw the dog back into horizontal position and in the movement of the dog from its upper 35 position to its horizontal position, the starting gear is thrown out of the path of the pinion of the engine shaft and into a locked inoperative position so as to reset the starter and to prevent injury to the operator and 40 to the parts of the starter.

When the head 39 of the dog is of such shape that it rides on the sides of adjacent teeth of the gear as shown in Fig. 11, in its movement from its upper position to its 45 lower position, as shown at B in Fig. 11, and as the dog is traveling on the arc of a circle, the movement is sufficient to throw the gear instantaneously out of mesh with the pinion of the engine shaft. This form 50 of head 39 permits using a shorter dog than one without such a head. As the gear is thrown out of mesh, the cables being released by the operator, the hanger and starting gear is returned to initial position by 55 the cable and locked in that position. As

the gear passes out of engagement with the dog, the flat spring 40 returns the same to its horizontal position and it will be seen that the spring 40 holds this dog normally in horizontal position and acts upon the 60 same when in either raised or lowered position.

In connection with the dog, I provide a locking device for locking the revolute starting member in mesh with the pinion 75 of the engine shaft, which comprises a locking bar 41 pivotally mounted upon the stud 26 and provided with the notched portion 42 which is adapted to be forced into engagement with the pin 28 by a coil spring 80 43 carried by the cotter pin of the stud 7 when the hanger is moved so as to throw the starting gear into mesh with the pinion of the engine shaft as shown in Fig. 4. This locking bar 41 is provided with a tail portion 85 44 which extends into the groove of the gear 10 and is adapted to be engaged by a projection 45 carried by the dog 38, which projection may or may not be adjustable as is herein shown in the form of a screw so 90 that the position of the engaging point can be adjusted in respect to the position of the tail of the locking bar. When the hanger and gear are released by pulling upon the pull cable, the locking bar drops from the 95 position shown in Fig. 3 into the position shown in Fig. 4 and holds the two coöperating gears in mesh so as to insure the starting of the engine. As shown in Fig. 4, when the parts are in operative position, 100 the dog 38 is in a position with its adjustable member 45 just out of contact with the tail 44 of the locking bar 42 and in case of a kick back or any reverse movement of the parts, the adjustable member 45 carried 105 by the dog 38 is instantaneously thrown into engagement with the tail 44 so as to raise the lock bar out of engagement with the pin 28 which allows the dog to throw the gear out of mesh with the pinion of the 110 engine shaft.

While I have shown and described a locking device used in connection with my improved construction of mechanical starter for holding the revolute starting gear in 115 mesh with the pinion of the engine shaft, the starting device will operate without the same and the provision of this locking device is only to insure the members being held in mesh when the cable is being drawn. 120 However, under ordinary circumstances, the pull on the cable is sufficient to hold the co-operating gears in mesh.

From the foregoing description, it will be seen that I have provided a mechanical 125 starter which comprises a revolute starting member mounted to intersect the path of travel of the pinion of the engine shaft by pulling upon a cable and adapted to be instantaneously thrown out of the path of 130

travel of the pinion of the engine shaft upon the back kick of the engine, means also being provided for locking the starting member in inoperative position so as to prevent the same from accidentally being thrown in the path of travel of the pinion of the engine shaft.

While I have shown a pull cable for operating the lever which has a connection with the operating cable of the starter it is, of course, understood that by mounting the lever adjacent the seat of the automobile, the same could be manipulated to accomplish the same result, but I have found by experimenting that the pull cable has many advantages over the direct pull upon the lever as the entire mechanism can be mounted within the hood of the automobile and the cable can be arranged in such a manner on the dash of the automobile that the same can be readily grasped by the operator to manipulate the same and that by having a flexible connection between the handle carried by the cable and the operating lever, it is impossible for the operator to be injured by the back kick of the engine.

While I have also shown and described a pull cable for operating the lever it is, of course, understood that any of the well-known forms of hand lever or foot lever now in use in devices of this kind can be installed in any convenient position so as to manipulate the starting device.

I claim:

35 1. In a mechanical starter, the combination with an engine shaft having a pinion mounted thereon, of a revoluble starting member mounted to intersect the path of travel of the pinion of the engine shaft, means for moving said gear into engagement with the pinion of the engine shaft and for rotating the same, and a movable member arranged in the path of travel of said starting member for throwing said starting member out of engagement with the pinion of the engine shaft upon the reverse movement thereof.

2. A mechanical starter, comprising a suspended member, having a revolubly mounted starting member mounted therein, a cable for moving said starting member into different positions and for rotating said starting member when in adjusted position, and a movable member arranged in the path of travel of said starting member for initially moving said starting member in one direction by the reverse rotation thereof.

3. In a mechanical starter, the combination with an engine shaft, a pinion mounted thereon, of a revoluble starting member mounted to intersect the path of travel of the pinion of the engine shaft, a cable connected to said revoluble starting member, a lever having a connection with said cable, a spring for normally holding said lever

in initial position, and a movable member arranged in the path of travel of said starting member and adapted to move said starting member out of engagement with the pinion of the engine shaft upon the reverse movement thereof.

4. A starting mechanism for explosive engines, comprising a revolubly mounted member mounted to move into and out of the path of a coöperating member carried by the engine shaft, means for moving and rotating said member in different directions, and a movable member arranged in the path of travel of said starting member and adapted to move said starting member out of engagement with the coöperating member of the engine shaft upon the reverse movement of said starting member.

5. A mechanical starter having a revolubly mounted starting member adapted to move in different paths, one of said paths intersecting the path of travel of a coöperating member carried by the engine shaft, means for rotating said starting member when in engagement with the coöperating member, and a movable member arranged in the path of travel of said starting member and adapted to move said starting member out of engagement with the coöperating member of the engine shaft when moved in a reverse direction.

6. In a mechanical starter for explosive engines, the combination with an engine shaft having a pinion mounted thereon, of a revolubly mounted starting gear mounted to move into and out of the path of travel of said pinion, an endless cable having a connection with said revolubly mounted gear for moving said gear into and out of the path of travel of said pinion, and a locking device arranged to automatically lock said gear in the path of travel of said pinion.

7. In a mechanical starter for automobiles, the combination with an engine shaft having a pinion fixed thereon, of a revolubly mounted starting gear mounted to move into and out of the path of travel of said pinion, means for rotating said starting gear in one direction, a movable member arranged in the path of travel of said starting gear and adapted to move said starting gear out of engagement with the pinion of the engine shaft upon the reverse movement thereof, and a locking device for locking said starting gear in engagement with the pinion of the engine shaft, said locking device coöperating with the movable member for releasing the same to allow said gear to be moved out of the path of travel of the pinion of the engine shaft.

8. A mechanical starter for explosive engines, comprising a supporting plate, a revolubly mounted member carried by said plate and mounted to move into and out of

- the path of a coöperating member carried by the engine shaft, an endless cable having a connection with said revolubly mounted member, means for operating said cable to throw said revolubly mounted member into mesh with the coöperating member of the engine shaft, and a locking device arranged to automatically lock the revolubly mounted member in mesh with the coöperating member of the engine shaft when moving in one direction and to release said locking device when the revolubly mounted member is moving in the reverse direction.
- 15 9. A starting mechanism for explosive engines, comprising a revolubly mounted member mounted to move into and out of the path of a coöperating member carried by the engine shaft, a cable for moving said revolubly mounted member into and out of the path of the coöperating member of the engine shaft, and means for locking said revolubly mounted member in the path of the coöperating member.
- 20 10. A starting mechanism for explosive engines, comprising a revolubly mounted member mounted to move into and out of the path of a coöperating member carried by the engine shaft, a cable having a connection with said revolubly mounted member for moving said revolubly mounted member into and out of the path of the coöperating member, a movable member arranged in the path of the revolubly mounted member and adapted to move said revolubly mounted member out of the path of the coöperating member of the engine shaft upon the reverse movement thereof, and a locking device for holding said revolubly mounted member in the path of the coöperating member of the engine shaft, said locking device being released by the movably mounted member.
- 25 11. A starting mechanism for explosive engines, comprising a revolubly mounted member mounted to move into and out of the path of the coöperating member carried by the engine shaft, an endless cable having a connection with said revolubly mounted member for moving said revolubly mounted member into and out of the path of the coöperating member of the engine shaft when moved in a reverse direction, and a locking device arranged and released by the movable member for locking said revolubly mounted member in the path of travel of the coöperating member of the engine shaft.
- 30 12. A starting member for explosive engines, comprising a revolubly mounted member mounted to move into and out of the path of the coöperating member carried by the engine shaft, an endless cable having a connection with said revolubly mounted member, a lever having a connection with one lead of said cable, a spring for normally holding said lever in one position, and a movable member arranged in the path of the revolubly mounted member and adapted to move said revolubly mounted member out of the path of the coöperating member of the engine shaft on the reverse movement of said revolubly mounted member.
- 35 13. A starting mechanism for explosive engines, comprising a revolubly mounted member mounted to move into and out of the path of the coöperating member carried by the engine shaft, a cable having a connection with said revolubly mounted member for moving said gear into and out of the path of the coöperating pinion of the engine shaft, and a movable member arranged in the path of the revolubly mounted gear for moving said gear out of the path of the coöperating pinion of the engine shaft on the reverse movement thereof and for releasing said locking means.
- 40 14. A mechanical starter, comprising a supporting plate, a hanger pivotally mounted upon said supporting plate, a starting member revolubly mounted in said hanger, a coöperating member mounted upon the engine shaft, a cable for moving said hanger to throw said starting member in and out of engagement with the coöperating member of the engine shaft, means carried by the hanger for locking said hanger when the starting member is out of engagement with the coöperating member, and a locking device arranged to automatically lock said hanger and starting member in engagement with the coöperating member.
- 45 15. A mechanical starter, comprising a supporting plate, a hanger pivotally mounted upon said supporting plate, a pin carried by said supporting plate, a starting member revolubly mounted in said hanger, a coöperating member mounted upon the engine shaft, a locking bar carried by said hanger and coöperating with said pin when said starting member is in engagement with the coöperating member, and a movable member arranged to automatically release said locking bar on the reverse movement of said starting member.
- 50 16. A mechanical starter, comprising a hanger having a starting gear revolubly mounted therein, an engine shaft having a coöperating pinion, said starting gear being capable of moving into and out of the path of the coöperating pinion carried by the engine shaft, a spring-actuated hook for holding said hanger when moved into one position, a spring lock for holding said

- hanger when moved into operative position, a projection carried by said gear for releasing said hook when moved in one direction, means for moving said hanger and rotating 5 said gear, and a movable member arranged in the path of the starting gear and adapted to release said locking means and move said starting gear out of the path of the coöperating member of the engine shaft.
- 10 17. A mechanical starter, comprising a supporting plate, a hanger pivotally mounted upon said supporting plate, a starting member revolubly mounted in said hanger, a coöperating member mounted upon the engine shaft, a pin projecting from said plate, a spring-actuated locking bar carried by said hanger and coöperating with said pin, and a movable member arranged in the path of said starting member and adapted to initially 15 release said locking device and to move said starting member out of the path of the coöperating member of the engine shaft upon the reverse movement thereof.
- 15 18. A mechanical starter, comprising a supporting plate, a hanger movably mounted upon said supporting plate, a starting member revolubly mounted in said hanger, a coöperating member mounted upon the engine shaft, an endless cable having a connection 20 with said revolubly mounted starting member for moving said starting member into and out of the path of travel of said coöperating member of the engine shaft, a locking device carried by said hanger for automatically 25 holding said starting member in engagement with the coöperating member of the engine shaft when said starting member is moving in one direction and means for releasing said locking device when said starting member is moving in a reverse direction.
- 20 19. A mechanical starter, comprising a supporting plate, a hanger pivotally mounted upon said plate, a revolubly mounted starting member carried by said hanger, an endless cable having a connection with said revolubly mounted starting member, a coöperating member mounted upon the engine shaft, means for operating said cable in one direction for moving said starting member into engagement with the coöperating member, and a movable member mounted upon said plate and arranged in the path of travel of said starting member for moving 25 said starting member out of engagement with said coöperating member of the engine shaft when revolved in a reverse direction.
- 25 20. A starting mechanism for explosive engines, comprising a revolubly mounted starting member mounted to move into and out of the path of a coöperating member carried by the engine shaft, an endless cable having a connection with said revolubly mounted starting member for moving said starting member into and out of the path of 30 the coöperating member of the engine shaft and for revolving the same, a movable member arranged in the path of the starting member for moving said starting member out of the path of the coöperating member when traveling in a reverse direction, and a locking device for holding said starting member in the path of the coöperating member of the engine shaft, said locking device being released by the movably mounted member upon the movement of the starting member in a reverse direction.
- 30 21. A mechanical starter, comprising a supporting plate, a hanger pivotally mounted upon said supporting plate, a revolubly mounted starting member carried by said hanger, a coöperating member mounted upon the engine shaft, a pin projecting from said plate, a locking device carried by said hanger coöperating with said pin for locking said starting member in inoperative position, a locking bar carried by said hanger and coöperating with said pin for locking said starting member in engagement with the coöperating member of the engine shaft, a cable having a connection with said starting member for moving said starting member into and out of the path of said coöperating member, and a movable member arranged in the path of the starting member and coöperating therewith for initially moving said starting member out of engagement with the coöperating member upon the reversal thereof, said movable member having means coöperating with the locking bar for releasing the same.
- 35 22. A mechanical starter, comprising a supporting plate, a hanger pivotally mounted upon said supporting plate, a spring-actuated hook carried by said hanger, a pin carried by said plate adapted to be engaged by said hook, a revoluble starting member carried by said hanger, a pin carried by said revoluble starting member coöperating with said hook for disengaging said hook from said pin, and an endless cable having a connection with said revoluble starting member for moving said revoluble starting member into and out of the path of travel of a coöperating member carried by the engine shaft.
- 40 23. A mechanical starter, comprising a supporting plate having a laterally projecting pin, a hanger pivotally mounted upon said plate, a revoluble grooved starting member carried by said hanger, a pivoted spring-actuated hook carried by said hanger coöperating with said pin, a finger extending from said hook, a pin carried by said revoluble starting member coöperating with said finger for disengaging said hook from said pin by the initial movement thereof, a spring-actuated locking bar carried by said hanger coöperating with the pin of the plate, an endless cable mounted within the groove
- 45 50 55 60 65 70 75 80 85 90 95 100 105 110 115 120 125 130

of the starting member, and means arranged in the path of travel of said starting member for releasing said locking means on the reverse movement of said starting member.

5 24. A mechanical starter, comprising a supporting plate, a pin projecting laterally from said plate, a hanger pivotally mounted upon said plate, a revoluble starting member mounted in said hanger, a spring-actuated locking bar carried by said hanger co-operating with said pin, and a movable member arranged in the path of travel of said starting member co-operating with the locking bar for releasing said locking bar 15 on the reverse movement of said starting member.

25. In a mechanical starter, the combination with an engine shaft having a pinion mounted thereon, of a revoluble starting member mounted to intersect the path of travel of said pinion, a cable for moving said starting member into and out of the path of travel of said pinion, and a movable member arranged in the path of travel 25 of said starting member for initially moving said starting member out of the path of travel of the pinion upon the reverse movement thereof.

26. In a mechanical starter, the combination with a revolubly mounted starting member, of a support for said revoluble starting member mounted to move said revoluble starting member into and out of the path of travel of a coöperating member carried by the engine shaft, a hook carried by said support for locking said starting member in inoperative position, a projection carried by said revoluble starting member co-operating with said hook for releasing the 40 same, an endless cable connected to said revoluble starting member, a lever connected to said cable, means for holding said lever in one position, and manually operated means for oscillating said lever.

45 27. In a mechanical starter, the combination with an engine shaft having a pinion mounted thereon, of a revoluble starting member mounted to intersect the path of travel of the pinion of the engine shaft, a locking device for holding said revoluble starting member in the path of the pinion of the engine shaft, and a member arranged 50 in the path of travel of said locking device for releasing said locking device on the reverse movement of said starting member.

28. An engine shaft, having a clutch cup, a clutch pin extending transversely through said cup, a pinion provided with a slotted sleeve extending into said cup and embracing said pin, and means for locking said sleeve within said cup.

29. A mechanical starter comprising a movable supporting member having a revolubly mounted starting member mounted 65 therein, a cable for moving said starting

member into different positions and for rotating said starting member when in adjusted position, means for locking said supporting member in either of its adjusted positions, and means for releasing said locking means. 70

30. In a mechanical starter, the combination with an engine shaft having a pinion, of a supporting plate adapted to span said engine shaft, a movable member mounted upon said supporting plate, a revoluble starting member carried by said movable member, a hook carried by said movable member, a pin carried by said supporting member coöperating with said hook for locking said revoluble starting member out of engagement with the pinion on the engine shaft, a locking bar carried by said movable member arranged to engage said pin, means carried by said revoluble starting member coöperating with said hook for releasing said hook on the initial rotation of said starting member, and a member arranged in the path of travel of said locking bar for releasing said hanger on the initial 80 rotation of said starting member in a reverse direction. 85

31. A mechanical starter comprising a suspended member, a revoluble starting member carried thereby, a hook carried by said suspended member, a lock bar carried by said suspended member, a pin arranged to be engaged by said hook and locking bar, means for throwing said locking bar out of engagement with said pin, and means carried by said revoluble starting member coöperating with said hook for disengaging said hook from said pin. 95

32. In a mechanical starter, the combination with a movable support, of a revoluble starting member mounted in said support, a cable connected to said revoluble starting member for rotating the same and for moving said movable support, means for locking said movable support in one position, means for releasing said locking means operated by the rotation of said starting member, a lock bar for locking said movable support in an opposite position, and a movable member arranged to disengage said locking 100 bar. 110

33. A mechanical starter for automobiles comprising a movable supporting member having a revoluble starting member carried thereby, a pin, a pivoted hook coöperating with said pin, a pivoted locking bar coöperating with said pin, independent means coöperating with said hook and locking bar for disengaging said locking bar and hook from said pin. 120

34. In a mechanical starter, the combination with an engine shaft having a pinion mounted thereon, of a revoluble starting member mounted to intersect the path of travel of the pinion on the engine shaft, 130

a movable support for said starting member, a cable for moving said revoluble starting member into and out of the path of travel of the pinion on the engine shaft, and for 5 rotating said starting member, means arranged in the path of said starting member for disengaging said starting member from said pinion upon the reversal of the rotation thereof, and means for locking said 10 starting member in operative or inoperative positions.

35. In a mechanical starter, the combination with an engine shaft having a pinion, of a revoluble starting member mounted to 15 intersect the path of travel of said pinion,

a movable support for said revoluble starting member, a locking bar carried by said movable support for locking said starting member in mesh with the pinion on the engine shaft, and a movable member coöperating 20 with said starting member for releasing said locking bar on the reverse rotation of the starting member.

In testimony whereof I hereunto affix my signature in the presence of two witnesses. 25

EDGAR B. STOCKING.
